(57) **CLAIM**

(51) LOC (7) Cl. **13-03**

The ornamental design for an integrated circuits substrate, as shown and described.

(52) U.S. Cl. **D13/182**

DESCRIPTION

(58) **Field of Search** D13/182; 174/52.2,

FIG. 1 is a front, top and right side perspective view of an integrated circuits substrate, showing my new design; FIG. 2 is a front elevational view thereof, the rear elevational view is omitted as that is symmetrical to the front elevational view thereof;

174/52.4; 257/666, 667, 676, 686, 690,

FIG. 3 is a top plan view thereof;

692, 696, 705, 712, 735; 361/742, 777,

FIG. 4 is a bottom plan view thereof;

813

FIG. 5 is a right side elevational view thereof;

(56) **References Cited**

FIG. 6 is a left side elevational view thereof; and,

U.S. PATENT DOCUMENTS

FIG. 7 is an enlarged cross-sectional view thereof, taken along line 7—7 of FIG. 2, with the internal system omitted.
